UNITED STATES PATENT OFFICE.

JOHN H. VICKERS, OF NORWICH, CONNECTICUT.

IMPROVEMENT IN COMBINED INHALERS AND DENTAL PROPS.

Specification forming part of Letters Patent No. 146,730, dated January 20, 1874; application filed October 10, 1873.

To all whom it may concern:

Be it known that I, JOHN H. VICKERS, of Norwich, in the county of New London and State of Connecticut, have invented certain new and useful Improvements in Dentists' Combined Mouth-Piece and Prop; and I do hereby declare the following to be a full, clear, and exact description of the invention, such as will enable others skilled in the art to which it pertains to make and use it, reference being had to the accompanying drawings, which form part of this specification.

This invention relates to the combination of that character of dentists' mouth-pieces used for inhaling gas, and dentists' props used for propping open the jaws, in such manner that, upon withdrawing the mouth-piece from the face after administering the gas, the prop will remain in the mouth, holding the jaws apart for the dentist's operations.

Figure 1 is a perspective view of my improved mouth-piece and prop when screwed into the usual metallic plate used to fit over the mouth. Fig. 2 is a sectional view of mouth-piece and prop detached therefrom. Fig. 3 is the prop with my spring attachment.

Like letters in the drawings indicate like parts.

From a dentist's ordinary mouth-piece, A A', used for inhaling gas, manufactured from wood, rubber, or other proper material, I cut out the section B, running through the center of the same, to the depth of the base C C'. The section cut away should be about one-half inch in width in ordinary-sized mouth-pieces. In such center space so formed I construct the prop B to fit closely and adjust easily. The

prop B is made of hard wood or other proper material of sufficient toughness to hold the jaws firmly apart, and is formed with a circular channel-way, E, lengthwise through the center of the same, such channel being for the admission of the gas, or for the passage of a gas-tube, if thought preferable to have a tube, part of A A' running through E, and connected with A A' at d' d of the base C C'. The top and bottom O O' of said prop B is made oval to correspond with the formation of the mouth-piece A, and to receive the bearing of the jaws when they are clasped together. On the bottom of the prop B, at K, I affix the spring I with its plate H, as shown. When the combined mouth-piece and prop is inserted in the mouth, the plate presses under the jaw by the power of the spring I, thus holding the prop in its proper position in the mouth when the mouth-piece is withdrawn.

What I claim as my invention, and desire to secure by Letters Patent, is—

1. The prop B, in combination with the mouth-piece A A', when constructed substantially as and for the purposes hereinbefore set forth.

2. The spring I with its plate H, in combination with the prop B, substantially as and for the purposes hereinbefore set forth.

In testimony that I claim the foregoing I have hereunto set my hand this 27th day of September, 1873.

JOHN H. VICKERS.
